UNITED STATES PATENT OFFICE.

LUTHER S. NEWCOMB, OF POMONA, KANSAS.

REIN-HOLDER FOR HARNESS.

SPECIFICATION forming part of Letters Patent No. 735,137, dated August 4, 1903.

Application filed October 31, 1901. Serial No. 80,672. (No model.)

To all whom it may concern:

Be it known that I, LUTHER S. NEWCOMB, a citizen of the United States, residing at Pomona, county of Franklin, State of Kansas, ⁵ have invented certain new and useful Improvements in Rein-Holders for Harness, of which the following is a specification.

My invention relates to rein-holders for harness.

10 The object of the invention is the provision of a rein-holder of simple and inexpensive construction which can be readily applied to the hip-strap at any desired point and will serve as a guide or holder for the rein, permitting free movement thereof, but preventing displacement either up or down, thereby preventing entanglement of the rein with the tail of the horse or its catching on parts of the harness. I aim particularly to provide a

15 device of the class described which will be small and not mar the general appearance of the harness and which will be light, strong, and durable and perform its function in a superior manner by being so positioned that

20 the rein will be held in correct position, so that it may not twist and will run easily.

Having the foregoing objects in view, the invention is embraced in certain features of construction set forth fully, and embodied in ²⁵ the appended claim.

In the accompanying drawings, Figure 1 is a view illustrating the application of the invention; Fig. 2, a perspective detail view; Fig. 3, a plan view, the dotted line being shown to illustrate how the guide-loop is inclined in relation to the buckle part of the device; and Fig. 4, a longitudinal section showing how the device is held to the hip-strap.

The invention is intended to be used on the ³⁰ hip-strap 1 of an ordinary harness, of which 2 denotes the reins.

The invention has a buckle composed of a back 3, provided with loops 4 and 5 at its extremities. A button 7, having buttoning-
45 point 8 projecting up through the back for engagement with the hip-strap 1, is secured

to the base by soldering. I may say here that the invention is intended to be constructed of thin metal suitably finished to give it a neat appearance, which will insure lightness ⁵⁰ and compactness of size.

The guide-loop for the rein is shown at 9, the same consisting of a piece of thin metal formed into a box-like loop by bending upon itself, with its ends 10 soldered, riveted, or ⁵⁵ suitably secured to the upper portion of the loop 5, with the guide-loop 9 so disposed in relation to the buckle part of the device that it is at an appreciable angle thereto—that is, offset laterally from the longitudinal axis of ⁶⁰ the buckle—and this for the purpose of bringing the eye of the loop 9 in such position that it will assume a straight position for the line or rein to run through, in consequence of which the rein is enabled to slip freely through ⁶⁵ the loop without twisting or kinking at the point where it runs therethrough. I consider this feature of importance in connection with the invention. It will be observed that the reins are held in proper position on ⁷⁰ the back of the animal and cannot turn or twist or become displaced to become entangled with the tail of the horse or any part of the harness.

Having thus described my invention, what ⁷⁵ I claim as new, and desire to secure by Letters Patent, is—

In a rein-guide, the combination with a relatively long buckle having a straight stiff back, and loops at each end of said back and raised ⁸⁰ thereabove, of a stiff guide rigidly secured at an angle to the longitudinal plane of the said buckle, said guide being attached to the top of one of said loops and projecting beyond, and a pin on said buckle for keeping it in adjusted position on the hip-strap. ⁸⁵

In testimony whereof I hereunto affix my signature in presence of two witnesses.

LUTHER S. NEWCOMB.
